UNITED STATES PATENT OFFICE

2,434,812

MIXER

Duane Roles, Toledo, Oreg.

Application September 7, 1945, Serial No. 614,840

2 Claims. (Cl. 259—105)

1

This invention relates to mixing devices and more particularly to a household mixer for mixing malted milk drinks and the like.

A main object of the invention is to provide a novel and improved mixing device of simple construction adapted to be mounted on the rim of a container such as a milk bottle and including means for drawing air into the container for mixing with the liquids contained therein during the agitation of said liquids by the device.

A further object of the invention is to provide an improved mixing device having components which are simple in structure and which are extremely easy to manufacture and assemble, and including means for resiliently mounting the device on the rim of a standard milk bottle or similar standard container in sealing relation thereto.

Other objects and advantages of the invention will appear from the following description and claims and from the accompanying drawings, wherein:

Figure 1 is an elevational view, partly in cross-section of a milk bottle upon which is mounted a mixing device in accordance with this invention.

Figure 2 is a cross-sectional view taken on line line 2—2 of Figure 1.

Figure 3 is a top view of the mixing device employed in Figure 1.

Referring to the drawings, 11 designates a moulded body of rubber or similar elastic material formed to be tightly fitted over the rim of a milk bottle 12 in gripping relationship therewith. Body 11 is provided with tab members 13, 13 adapted to be grasped by the operator in mounting the device on the bottle or removing the device from its mounted position on the bottle.

Body 11 is formed with an integral upstanding sleeve 14 in which a cylindrical metal sleeve 15 is positioned. Rotatably mounted in body 11 centrally thereof is a depending vertical tubular member 16 formed with a helical flange 17. The top end of tubular member 16 is formed with a bevel gear 18 integral therewith which rests on a washer 19. Washer 19 serves as a bearing member for rotatably supporting bevel gear 18 and tubular member 16 axially with respect to body 11, the central part of the gear being open to permit passage of air downward through the tube into the bottle.

Meshed with bevel gear 18 is a vertical bevel gear 20 carried on a horizontal shaft 21 projecting laterally through sleeve 15 and sleeve 14. Shaft 21 is formed with a square end for releasable engagement with a crank member 22. Shaft 21

2

21 is rotatably supported in a metal bearing washer 23 carried by sleeve 14 and is formed with an integral spacing collar 24.

Positioned axially in tubular member 16 is a shaft 25 which carries at its bottom end an agitator vane 26 formed of a wire loop having cross bars 27 secured thereto. Adjacent its upper end rod 25 is rotatably mounted in a bearing 25 and has mounted thereon a bevel gear 28 which meshes with the bevel gear 20. Above bevel gear 28, rod 25 carries a fan member 29 adapted to circulate air into tubular member 16 through the opening in the central part of the gear 28 when rod 25 is rotated. The top end of rod 25 carries a chuck collar 30 for at times coupling the rod to a power device such as an electric motor.

When the mixing device is actuated either by manual rotation of crank member 22 or by power actuation of shaft 25, tubular member 16 is rotated in one direction and agitator vane 26 is rotated in the opposite direction. At the same time air is blown into the bottle 12 by fan member 29, through the tube 16 and with the air escaping from the bottle through openings 31 in the cap 11.

25 The liquids in the bottle are thus agitated and thoroughly mixed with air, producing a desired aerated mixed drink, such as a malted milk drink when the proper ingredients therefor are employed. Of course, other aerated liquid mixtures 30 may be produced by the device if desired.

Spilling of liquid during the mixing process is prevented by resilient body 11 which embraces the bottle rim in sealing relation thereto.

While a specific embodiment of a mixing device has been disclosed in the foregoing description, it will be understood that various modifications within the spirit of the invention may occur to those skilled in the art. Therefore it is intended that no limitations be placed on the invention other than as defined by the scope of the appended claims.

What is claimed is:

1. In a mechanical mixer for mixing elements in an open top container, a cap adapted for being removably positioned upon said open top container, said cap having openings extending therethrough from the exterior surface thereof to communicate with the interior of said container, a sleeve carried by the top of said cap, a shaft 45 mounted in said sleeve extending into said container, an agitating element on a portion of the shaft extending into said container, a tubular member surrounding a substantial portion of said shaft mounted in said cap and extending into said container, agitating means on the portion

of said tubular member extending into said container, a rotating element on said tubular member positioned within said sleeve and spaced above said cap, said rotating element having an opening therein communicating with the interior of said tubular member, a rotating element on the shaft within said sleeve positioned above and spaced from the rotating element on said tubular member, a rotative element mounted in said sleeve and operatively connected with the rotating elements on said shaft and tubular member respectively adapted to rotate said elements in opposite directions, a fan on the shaft positioned within said sleeve above and spaced from the rotating element on the shaft adapted for feeding air downwardly through the tubular member and into the elements being mixed in the container, and means for rotating said rotative element from the exterior of said sleeve.

2. In a mechanical mixer for mixing elements in an open top container, a cap adapted for being removably positioned upon said open top container, said cap having openings extending therethrough from the exterior surface thereof to communicate with the interior of said container, a sleeve carried by the top of said cap, a shaft mounted in said sleeve extending into said container, an agitating element on a portion of the shaft extending into said container, a tubular member surrounding a substantial portion of said shaft mounted in said cap and extending into said container, agitating means on the portion of said tubular member extending into said con-

tainer, a gear on said tubular member positioned within said sleeve and spaced above said cap, said gear having an opening therein communicating with the interior of said tubular member, a gear on the shaft within said sleeve positioned above and spaced from the gear on said tubular member, a gear rotatively mounted in said sleeve and meshing with the gears on said shaft and tubular member respectively adapted to rotate said gears in opposite directions, a fan on the shaft positioned within said sleeve above and spaced from the gear on the shaft adapted for feeding air downwardly through the tubular member and into the elements being mixed in the container, and means for rotating said rotative gear from the exterior of said sleeve.
